CLAIM

The ornamental design for a combined cash register and bar code reader toy, as shown and described.

DESCRIPTION

FIG. 1 is a front perspective view of the combined cash register and bar code reader toy showing my new design;

FIG. 2 is a top plan view thereof;

FIG. 3 is a right side elevational view thereof;

FIG. 4 is a left side elevational view thereof;

FIG. 5 is a front elevational view thereof;

FIG. 6 is a rear elevational view thereof; and

FIG. 7 is a bottom plan view thereof.
